UNITED STATES PATENT OFFICE.

JOSEPH MUNGER, OF WATERBURY, CONNECTICUT, ASSIGNOR TO THE SCOVILL MANUFACTURING COMPANY, OF SAME PLACE.

PAPER FILE OR CLIP.

SPECIFICATION forming part of Letters Patent No. 363,533, dated May 24, 1887.

Application filed February 10, 1887. Serial No. 227,006. (No model.)

To all whom it may concern:

Be it known that I, JOSEPH MUNGER, of Waterbury, in the county of New Haven and State of Connecticut, have invented a new and useful Improvement in Paper Files or Clips, of which the following is a specification.

My invention relates to paper files or clips which comprise two hinged members or jaws having projecting finger pieces, whereby they may be sprung apart or opened, and a spring for closing the jaws and holding them together at their biting-edges with an elastic and yielding pressure.

An important object of my invention is to provide for the employment in such a file or clip of a C-shaped spring which may be applied without any riveting, and which is so arranged that it is protected and held in place by the finger-pieces.

The invention will be hereinafter fully described, and pointed out in the claims.

In the accompanying drawings, Figure 1 is a side view of a file or clip embodying my invention. Fig. 2 is an end view thereof; and Fig. 3 is a transverse section upon about the plane indicated by the dotted line x x , Fig. 1.

Similar letters of reference designate corresponding parts in the several figures.

A designates the two jaws or members, which are, in this example of the invention, long and of little width, and which are hinged or pivoted together along their longitudinal edges at b . The opposite edges, b' , of the jaws or members A form their biting or holding portions, and the two jaws or members are concavo-convex in a plane transverse to the axis of the pivot b , which connects them, or are of like form or duplicates each of the other. By this form the jaws or members are given a bearing at their edges only, and they more effectively hold the papers inserted between them.

From the hinged edges of the jaws A extend finger-pieces B, which, as here shown, are made separate from the jaws and secured to them by rivets c , or otherwise. The parts of the file or clip are stamped or cut out from sheet metal by suitable dies, and when the

finger-pieces B are made separate from the jaws or members and secured to them the metal can be cut with less waste or scrap.

C designates a spring, which is C-shaped, as shown best in Fig. 3, and has its ends c' hooked, as also shown in Fig. 3. This spring is arranged so as to be shielded and held in place by the finger-pieces B; and in this example of my invention the finger-pieces are formed with slots b^2 , which are of a width slightly greater than the width of the spring C, and the said spring is arranged within the slots of the two finger-pieces, as shown in Figs. 1 and 3. Extending inward from the opposite walls of the slots b^2 in the finger-pieces B are spurs or projections b^3 , with which the hooked ends c' of the spring C engage, and the spring therefore exerts its force to close the edges b' of the jaws or members upon the papers inserted between them. By this construction the spring is held in place and has its ends so connected with the jaws or member that no rivets or other devices are needed to properly secure the spring in place. Through the finger-pieces B the ends of the spring are connected with the jaws or members.

Instead of forming separate projections or spurs b^3 at opposite walls of the slots b^2 , the finger-pieces may be formed with the cross-bar, as shown by dotted lines, Fig. 1, for the engagement of the hooked end c' of the spring.

It will be observed that the two jaws A are duplicates each of the other, and that the finger-pieces B are also duplicates each of the other, and the jaws are concavo-convex in their transverse section. Hence both jaws may be formed with the same dies, and both finger-pieces can also be formed with the same dies. When the jaws are both concavo-convex, their gripping-edges have a better hold upon papers than when one jaw has a flat face.

What I claim as my invention, and desire to secure by Letters Patent, is—

1. The paper file or clip herein described, composed of two jaws or members hinged together at one longitudinal edge and having finger-pieces projecting from them, and a C-shaped spring having its opposite ends

hooked and applied to close the jaws or members, substantially as herein set forth.

2. The paper file or clip herein described, composed of two jaws or members hinged together at one edge and having the slotted finger-pieces projecting from their hinged edges, and the C-shaped spring C, for closing

the jaws or members, arranged in the slots of the finger-pieces, substantially as herein set forth.

JOSEPH MUNGER.
